(57) **CLAIM**

The ornamental design for a front portion for an automobile, as shown and described.

DESCRIPTION

FIG. 1 is a front perspective view of a front portion for an automobile showing our new design;

FIG. 2 is a rear perspective view thereof;

FIG. 3 is a front view thereof;

FIG. 4 is a rear view thereof;

FIG. 5 is a top view thereof;

FIG. 6 is a right side view thereof; and,

FIG. 7 is a left side view thereof.

The claimed design comprises the shape and configuration of the relatively dark portions of FIGS. 1-7 surrounded by broken lines. The relatively light portions of FIGS. 1-7 found outside the broken lines form no part of the claimed design.
